CONTAINER

George Arlington Moore, Louisville, Ky., assignor
to Humco Corporation, Louisville, Ky., a corporation of Delaware

Application August 23, 1935, Serial No. 37,439

7 Claims. (Cl. 229—43)

This invention relates to containers, and more particularly to closure means for a container.

One of the objects of the present invention is to provide a novel cover for a container having at least two substantially parallel side walls.

Another object of the invention is to provide a novel sliding closure for containers which is adapted to be readily manipulated by the user and one which may be employed with containers formed of various substances, such as paper, fiber, or the like.

Another object is to provide a molded closure member in combination with a sealed container whereby the closure member may be opened to give access to a frangible seal, and may be readily closed, after the hatch in the seal has been opened or removed, to prevent loss of the contents of the container.

A further object is to provide, in combination with a container, a novel cover adapted to be readily moved from closed position to open position, one which will remain in the open position to which it is moved but which may be readily returned to and yieldingly held in closed position.

Other objects include the provision of a novel cover which is inexpensive to manufacture, pleasing in appearance, readily combined with the container or removed therefrom, one which may be molded, and one which is adapted for use with containers of various sizes, and especially those containers having two parallel side walls, such as an oblong container or a rectangular container.

The above and other objects and advantages will appear more fully hereafter in the detailed description of the invention, which description is to be read in connection with the accompanying drawings illustrating three embodiments of the invention. It is to be expressly understood, however, that the drawings are for purposes of illustration only and are not designed as a definition of the limits of the invention, reference being primarily had for this purpose to the appended claims. In the drawings, wherein like reference characters refer to like parts throughout the several views,

Fig. 1 is a side elevation showing a container provided with a cover embodying the present invention;

Fig. 2 is an end view of the right-hand end, as viewed in Fig. 1, of the container with the novel cover in closed position;

Fig. 3 is a detail side view of a container fitted with a second embodiment of the invention;

Fig. 4 is a detail end view of the left-hand

end, as viewed in Fig. 1, of the container and closure illustrated in the last mentioned figure;

Fig. 5 is an enlarged sectional view, with parts broken away, illustrating the cover of the invention in closed position on a paper or fiber container having a removable hatch;

Fig. 6 is a view similar to Fig. 5 with the cover and hatch in open position;

Fig. 7 is a perspective view, with parts broken away, illustrating the novel closure of the present invention in partially open position on a container, prior to the opening of the hatch of the container;

Fig. 8 is a bottom plan view of the cover shown in Fig. 7;

Fig. 9 is a section taken on the line 9—9 of Fig. 8;

Fig. 10 is a transverse sectional view of the container, hatch and closure shown in Fig. 7;

Fig. 11 is an enlarged detail section, with parts broken away, illustrating a third embodiment of the cover of the present invention.

It has heretofore been proposed by me to provide an oblong paper container having transversely extending and inwardly projecting ribs in the two parallel walls of the body thereof, the opposite ends of said ribs extending for a short distance into the arcuate end walls of the container, as shown in Figs. 1, 4 and 7. The novel cover of the present invention is particularly adapted for use in combination with a container of this type, since, in the illustrated embodiment, the same comprises a head or horizontal portion 12 (Figs. 7, 8 and 9) which is preferably surrounded, on its upper face, by a bead or strengthening rib 13 and a peripheral flange portion 14. In the form shown, the head is oblong and is curved at its opposite ends, the side edges of the same being substantially rectilinear and parallel. The flange does not extend throughout the periphery of the cover, but preferably terminates along the two sides at points on a line drawn through the center of the radius of curvature of the adjacent end of the head and at right angles to the longitudinal axis of said cover.

Formed integrally with the lower edges of the two parallel walls of the flange are beads 15 which are substantially round in cross section and which are adapted to extend into grooves 16 provided in the side walls of container 17 adjacent the upper end of the latter. As shown in Fig. 10, grooves 16 preferably have a portion 16a extending inwardly at an angle of approxi-

mately 45°, a vertical portion 16b and a horizontal portion 16c forming an inwardly extending shoulder for a purpose to be described hereafter. These ribs may be formed in the body 5 walls by means of dies. It will be noted that the center of the bead 15 is displaced inwardly relative to the flange 14 so that said bead has frictional engagement with the inclined wall 16a, and that a portion of the bead on the inner 10 surface thereof where it merges with the flange 14, has close engagement with the outer surface of the outer portion of the shoulder 16c. The upper, inner surface of the flange where it joins the head 12 is curved to closely engage the upper 15 curved surface of the edge 19 of the container.

The distance between the edge 19 and the bottom of shoulder 16c of the container is preferably slightly greater than the distance between the inner curved surface of the cover below bead 13 20 and that portion of bead 15 which engages shoulder 16c. This insures that the cover will be frictionally held in any open position to which it is adjusted, as that shown in Fig. 7. The difference in the dimensions of the parts mentioned is, of 25 course, slight, and if the materials of which the cover and container are formed are not unusually smooth, it may be unnecessary to provide any difference in the dimensions to obtain the necessary frictional engagement.

30 Preferably, head 12 is provided on its upper surface with a friction member 20 (Fig. 7) constituting a thumb grip which may be formed by embossing a suitable design on said head, whereby the user can readily slide the cover along the container to open or closed position. In the embodiment illustrated, no stop is provided to limit the movement of the cover to the right, as viewed in Figs. 1 and 7. When moved to the left, however, the curved end 21 of the flange engages the adjacent end of the container to limit the movement 40 of said cover so that the upper end of the container is closed without any portion of the left hand end of the cover overhanging the side wall of said container. As illustrated more clearly in 45 Figs. 8 and 9, the beads 15 on the lower edges of the flanges do not extend around the arcuate portion 21 of the flange, but merge into said arcuate portion so that the beads throughout are rectilinear. This facilitates molding of the cover.

50 If desired, the arcuate portion 21 of flange 14 may be eliminated, so that the cover comprises a head 22 and flanges 23 (Fig. 3), each flange being of less length than the head 22 and being centrally disposed relative to the container when the cover is closed.

55 The beads on the lower edge of the flange may correspond in cross section to the outer surface of the inwardly extending rib 16a, 16b, 16c. In Fig. 11 there is illustrated a bead 24 of this character which may be used where it is desired to increase frictional engagement between the side wall of the groove and the cover.

60 Preferably, the novel cover of the present invention embodies means for yieldingly retaining the cover in closed position. In the form shown, an overhanging lip 25 is formed on the lower face of head 12 to coat with the curved upper edge 17 of the side wall of the container. Preferably, said side wall is formed of a substance, such as paper, fiber or other suitable moldable material, and the cover itself may be molded from a suitable plastic, such as Bakelite, a pigmented acetate, or may be fabricated of fiber. Thus, when the user 65 moves the cover to the right, as viewed in Fig. 5, by applying pressure on the friction surface 20,

there is a sufficient yielding of head 12, lip 25 and the upper edge 19 of the side wall so that the lip 25 moves over the edge 19 to the position illustrated in Figs. 6 and 7. Preferably, the lip 25 has an arcuate length of approximately one-third of the length of the curved end of the cover (Fig. 8).

5 The novel cover disclosed herein is adapted for use with a hermetically sealed container having a removable hatch. As shown more clearly in Figs. 10 5, 6, 7 and 10, a closure member 26 is provided for the upper end of container 17. This closure member, which rests on the shoulder 16c formed by the ribs 16, comprises a flanged portion 27 which is positioned between the side wall of the 15 container and an inflowed portion 17a of said side wall to provide a closure formation, the flange 27 being preferably joined to the central portion of the closure by means of an arcuate portion 28. In the embodiment illustrated, member 26 is laminated, the inner lamina being constituted by a 20 suitable sheet of fiber 29 or similar material, such as paper, and the outer lamina being formed of metallic foil 30. A furrow 31 is plowed in the inner lamina in such a manner as not to destroy 25 the foil 30, said furrow having an oblong outline corresponding to the shape of the container and extending around the periphery of closure 26 closely adjacent the inner end of the arcuate portion 28.

30 When it is desired to remove the contents of the container, the cover is moved to a position such as that shown in Fig. 6, whereupon pressure is applied with the finger to one end of the hatch constituted by the laminated member 29, 30 to shear 35 the foil in the plane of furrow 31 and force the hatch inwardly to the dot and dash line position illustrated. If desired, a pressure locating button 32 (Fig. 7) may be provided in the hatch to facilitate the opening of the same. As the hatch 40 is forced inwardly, the same bends along the outwardly pressed rib 33, and if the finger of the user is then drawn toward his thumb, the inwardly extending portion of the hatch is raised to bend along said rib 33, and an adjacent similar rib 34. 45 The contents of the container may now be discharged, whereupon the hatch may be pressed downwardly to substantially closed position and the cover slid back into closed position with lip 25 overhanging edge 19 of the container. If desired, the user may remove the hatch entirely 50 from the container, the two sections 26a and 26b of said hatch acting as a tab to facilitate the breaking of the seal in the plane of the furrow throughout the entire periphery of the hatch. 55

55 In certain types of containers it may be desirable to increase the frictional engagement between the cover and the container and to provide means for accurately centering the cover in closed position. For this purpose, the container and 60 cover may have cooperating projecting portions and recesses to center the cover in closed position and provide for additional friction between the cover and container wall when the cover is being moved. As shown in Figs. 3 and 10, the container 65 is provided with recesses adapted to receive projections or buttons 35 formed on the inner face of each flange 14 of the cover. When the cover is moved to open position, projections 35 ride out of the recesses, moving parallel to the upper edge of 70 the container, tending to bend the parallel side walls of the container inwardly and increasing the frictional engagement between the container and cover whereby the cover is held in adjusted open position. When the cover is returned to 75

closed position, projections 35 move into the recesses and the user is informed without looking, due to the change in resistance to movement of the cover at this time, that said cover is returned to closed position. The use of the recesses and projections referred to may, at certain instances, eliminate the necessity for use of lips 25.

Preferably, the novel cover of the present invention is molded from Bakelite or other suitable acetate. These plastic materials readily lend themselves to coloring and molding and may be very inexpensively produced in large quantities. It will be understood, however, that the invention is not limited to any particular material, since the cover may be molded from fibrous material such as paper or pulp, if desired, or may be fabricated from fiber. The container may also be formed from a wide variety of substances, such as paper or fiber or other plastics, although a certain amount of yield is desirable in the container as well as in the cover in order that the latter may be yieldingly maintained in closed position. When the cover is used with a container having an impervious removable hatch of the character described, the hatch is protected by the cover against accidental fracture and after the hatch is removed, the cover effectively prevents the discharge of the contents. The cover is particularly adapted to permit free discharge of the contents of the container. The invention is not limited to an oblong shape, since those skilled in the art will see that the same is applicable to containers and covers of rectangular shape. Various designs may be employed for the thumb grip, as, for example, the trade-mark of the user may be embossed in the head. The ribs in the side wall of the container may project outwardly, rather than inwardly, as in the illustrated preferred form. The embodiment shown in Fig. 3 may have a lip at each end thereof or, if desired, one or both lips may be eliminated and projections 35 with cooperating recesses may be relied on entirely to insure that the cover will be retained in fully closed position. Reference will accordingly be had to the appended claims for a definition of the limits of the invention.

What is claimed is:

1. A cover for a container comprising a head portion having a lip on the lower face thereof adjacent one end adapted to coact with the edge 50 of the container, a flange depending from said head portion and extending through a major portion of the periphery of the head, said flange having two substantially parallel side wall portions, and inwardly extending beads carried by 55 said side wall portions adapted to coact with grooves in the walls of the container.

2. The combination, with a container having two substantially parallel side walls with ribs in said walls extending substantially parallel to the upper edges of said side walls, of a closure for the container having a portion thereof supported by said ribs, and a slidable cover for said container, said cover having flanges provided with beads adjacent the lower edges thereof for frictional engagement with the walls of said ribs. 5

3. In combination, with a fiber container having an open end, grooves in two parallel walls of said container, said grooves being adjacent and substantially parallel to said open end, a molded cover for the upper end of the container, flanges on said cover adapted to engage the parallel side walls of the container, beads on said flanges adapted to engage the walls of said grooves to position the cover on the container and guide the same in sliding engagement with said container, and friction means for resisting sliding movement of the cover from central closed position. 10

4. In combination with a container having two substantially parallel side walls with grooves therein disposed parallel to the rounded edges of the open end of the container, a slidable cover having a portion engaging said grooves to position and guide said cover and having a downwardly extending lip adapted to overhang the rounded edge of the container for yieldingly holding the cover in closed position. 25

5. A slidable cover for a container comprising a molded head portion having a peripheral bead on the upper face thereof, a depending peripheral flange carrying beads on the lower edge thereof, and a downwardly projecting lip on the lower face of the head portion adjacent one end thereof. 35

6. In combination with a container having inwardly extending ribs constituting a support for a frangible flanged closure, a molded cover for said container adapted to slide on the edge of said side walls of the container and having a portion engaging said ribs to position and guide said cover relative to the container. 40

7. In combination with an oblong container having grooves in the side walls thereof extending parallel to the upper edges of the container, a flanged, laterally slidable cover for the container, the flange of the cover being interrupted and having portions extending into said grooves and the dimensions of said cover and container being such that the head of the cover and said extending portions of the flange exert a gripping action on the container. 45

GEORGE ARLINGTON MOORE. 55
